UNITED STATES PATENT OFFICE

WILLIAM H. CAMFIELD, OF NEWARK, NEW JERSEY

DESIGN FOR A PEN HOLDER

Application filed February 26, 1931. Serial No. 38,830. Term of patent 3½ years.

To all whom it may concern:

Be it known that I, WILLIAM H. CAMFIELD, a citizen of the United States, residing in Newark, in the county of Essex and State of New Jersey, have invented a new, original, and ornamental Design for Pen Holders, of which the following is a specification, reference being had to the accompanying drawings, forming part thereof.

I claim:

The ornamental design for a pen holder, as shown.

WM. H. CAMFIELD.
